UNITED STATES PATENT OFFICE.

EDWARD F. DIAMOND, OF OAKLAND, CALIFORNIA.

EMERGENCY-SHACKLE.

SPECIFICATION forming part of Letters Patent No. 696,136, dated March 25, 1902.

Application filed December 30, 1901. Serial No. 87,740. (No model.)

To all whom it may concern:

Be it known that I, EDWARD F. DIAMOND, a citizen of the United States, residing in Oakland, county of Alameda, State of California, 5 have invented an Improvement in Emergency-Shackles; and I hereby declare the following to be a full, clear, and exact description of the same.

My invention relates to a device for coupling cars in case of an emergency, and which 10 I term an "emergency-shackle."

It consists of the parts and the constructions and combinations of parts which I will hereinafter describe and claim.

15 Figure 1 shows the application of the shackles. Fig. 2 is a detached view of the same.

Car-couplings often become broken or disabled in use to such an extent that the coupling-lugs or other parts cannot be employed 20 for connecting the cars.

It is the object of my invention to provide a simple means for connecting cars under such conditions, so that they may continue 25 their journey.

I have here shown my invention as applied to that class of couplings in which the draw-heads have interlocking knuckles; but it may be applied to any coupling in which the draw- 30 head has an enlarged portion sufficiently protuberant for the engagement of the yokes which form a part of my invention.

A A are yokes made of metal of sufficient size and strength and of such shape as will 35 fit over the shank or similar portions of draw-heads 2 of the class in use upon the railway where the device is to be employed. As shown in the present case, these yokes are approximately rectangular in shape, having 40 a top and two vertical sides, forming forks, which will fit over the draw-head, as above stated. These draw-heads usually have an elevated shoulder 3, and the yokes A drop down over the draw-head shank behind these 45 shoulders or elevations, which thus serve as abutments against which the upper portions of the yokes contact and by which they may be prevented from being drawn forward. The lower ends of these yokes are enlarged 50 and have holes made through them for the passage of pins 4. These pins may have heads upon one end and slots for the reception of keys, as at 5, at the opposite end, and the side

arms of the yokes are long enough to extend just below the draw-head shank, so that when 55 in position the pins can be put through and the keys 5 or other means of securing them applied, so as to prevent their being withdrawn. A chain is made having the alternately long and short links 6 and 7, the object of which is to allow the device to be adjusted to varying distances which may occur between the yokes when they are in place, the long and short links allowing for variations in adjustment when the chain has been 60 attached.

The application would then be as follows: The cars being brought as close together as possible, the yokes are dropped over the draw-bars and the pins 4 pass through the holes in 70 the lower ends, passing beneath the draw-bars, and the lower ends are then drawn toward each other as far as the configuration of the draw-heads will allow and the chain previously attached to one of the pins. The 75 other end can then be attached to the opposite one either by passing the pin through a link of the chain or by other convenient means, when the device will be in condition for use, and the car may be readily hauled to some 80 more convenient point, or in some cases it may continue the journey to its terminus.

Having thus described my invention, what I claim, and desire to secure by Letters Patent, is—

1. An emergency-shackle for cars consisting of yokes open at one side adapted to fit over the draw-heads of the cars, pins or rods extending through holes to connect the open sides of the yokes and chains extending between the pins and connected with each. 85

2. An emergency-shackle for cars consisting of rectangular yokes having an open side, holes made through the ends of the side bars, pins or rods adapted to extend through and 90 connect said ends when the yoke is in place upon the draw-head and a chain having alternate long and short links whereby it is adjustably fitted to connect the pins of the yokes and complete the coupling. 100

In witness whereof I have hereunto set my hand.

EDWARD F. DIAMOND.
